CHAIR

Robert D. Vanderminden, Granville, N. Y., assignor to
The Telescope Folding Furniture Co., Inc., Granville,
N. Y., a corporation of New York

Application December 28, 1956, Serial No. 44,344

Term of patent 14 years

(Cl. D15—1)

Fig. 1

Fig. 2

FIG.3

Figure 1 is a front perspective view of a chair embodying the design;

Figure 2 is a side perspective view of the said chair; and

Figure 3 is an elevated front perspective view of the chair taken from a different angle to that of Figure 1.

The dominant features of my design reside in the contrasting appearance between the wooden back rest, seat, arm rests, stretchers and leg tips, and the metal legs and back rest supports all as shown.

I claim:

The ornamental design for a chair, as shown and described.
